Primary Examiner — Sandra Snapp*Assistant Examiner* — Dustin Andrew Griffith(74) Attorney, Agent, or Firm — Richard Eldredge; Leavitt Eldredge Law Firm(57) CLAIM

The ornamental design for a game bag as shown and described.

DESCRIPTION

FIG. 1 is an isometric view of a game bag in accordance with the present design.

FIG. 2 is a front view of the game bag.

FIG. 3 is a back view of the game bag.

FIG. 4 is a first side view of the game bag.

FIG. 5 is a second side view of the game bag.

FIG. 6 is a top view of the game bag; and,

FIG. 7 is a bottom view of the game bag.

The broken lines show elements of the present design that do not form part of the claimed design.
